ROBERT A. THOMSON, OF BERKELEY, AND GORDON ALVIS, OF OAKLAND, CALIFORNIA.

DOLL.

1,343,422.

Specification of Letters Patent. Patented June 15, 1920.

Application filed August 21, 1919. Serial No. 318,969.

To all whom it may concern:

Be it known that we, ROBERT A. THOMSON and GORDON ALVIS, citizens of the United States, residing the said THOMSON at 5 Berkeley, in the county of Alameda and State of California, and the said ALVIS at Oakland, in the county of Alameda, State of California, have invented certain new and useful Improvements in Dolls, of which the following is a specification.

Our invention relates to improvements in dolls of the type having movable or self-closing eyes.

The object of our invention is to provide 15 a doll of the described type, in which the eyes are automatically and gradually closed by the act of rocking the doll from side to side while in a recumbent position, and opened again, with a relatively rapid movement, by raising the doll to an upright position. Thus the doll is made to simulate the 20 actions and appearance of a living child in gradually closing its eyes, as if going to sleep, when rocked from side to side in a 25 recumbent position, and in opening its eyes, as if awakening, when raised to an upright position.

The invention will be more fully described hereinafter with reference to the 30 accompanying drawings, wherein:

Figure 1 is a perspective view of a doll's head embodying our invention.

Fig. 2 is a horizontal section of the same, in the plane of the eye-balls.

Fig. 3 is a vertical section taken on the line $\alpha-\alpha$ of Fig. 2, showing the position of the movable parts when the head is in an upright position.

Fig. 4 is a view similar to Fig. 3, showing 40 the position of the movable parts when the head is in a horizontal or recumbent position.

In the drawings, the reference numeral 1 45 designates the head of a doll, which is formed in the usual manner, and is hollow, and provided with the usual eye-sockets 2. Eye-balls 3, positioned to appear, from the front, through the apertures of said sockets 2, are provided in the usual manner with 50 glass or other fronts 4, Fig. 2 to represent the cornea, iris and pupil of the eyes, above which are painted or formed eye-lids 5. The eye-balls are connected to operate in unison, by a bridge 6, and are mounted in

their sockets for oscillatory movement about 55 a horizontal axis, in the well known manner, so that when said eye-balls are rotated upwardly the cornea or open eye 4 appears through the apertures of the sockets 2, and when rotated downwardly, the lids 5 appear, giving the life-like impression of eye-lids descending over the eyes.

From the bridge 6 is extended, rearwardly and downwardly, a pendulum-rod 7, Figs. 1, 3 and 4, having a pivotal connection 8 to 65 permit lateral swing, and a weight 9. The free end portion 10 of said pendulum-rod lies within a slot 11 formed in an arcuate member 12, secured to the head 1, interiorly at 13 and 14, Figs. 3 and 4, said slot having 70 its edges provided with staggered teeth 15 whose lower faces 16, Figs. 1 and 2, are perpendicular to the longitudinal axis of said slot, and whose upper faces 17 are inclined, 75 as shown.

Thus, when the head 1 is placed in a horizontal or recumbent position, as shown in Fig. 4, the weighted-rod 7 is prevented from traveling freely to the then lower end of the slot 11, by the engagement of its end 80 portion 10 with the perpendicular faces 16 of the teeth 15; but by rocking the head 1 from side to side, the weight of the rod 7 causes said end portion 10 to alternately slip out from behind each tooth 15 and fall into 85 engagement with the next tooth on the opposite side of the slot 11, thus intermittently progressing in a zig-zag path toward the then lower end of the slot the distance of one tooth at each lateral movement of the 90 head 1. When the head is again returned to an upright position, as shown in Fig. 3, the pendulum-rod 7 returns freely and rapidly by its own weight to its former position, the end portion 10 easily riding over 95 the inclined faces 17 of the teeth 15 and following the slot 11 to the then lower end.

Therefore, when the head 1 is first placed in a recumbent position, the eye-balls 3 do not at once move, but upon lateral rocking 100 of said head, said eye-balls gradually or intermittently progressively assume the position wherein the eye-lids 5 only appear through the apertures of the sockets 2, giving the appearance of a gradual closing of 105 the eyes, as in falling to sleep; and when the head is again placed in an upright position, the eye-balls 3 return at once, freely

and rapidly, to their former position, giving the appearance of a rapid opening of the eyes, as in the act of awakening.

We claim:—

- 5 In a doll having eyes mounted for oscillation to and from an open and a closed position, a weighted rod connected with said eyes to close them when the doll is recumbent and to open them when the doll is upright; a joint in said weighted rod adapting it to swing laterally; and a slotted guide in which the weighted rod plays in moving the eyes, said guide having opposing staggered teeth arranged to successively and oppositely engage the rod
- 10
- 15

in its lateral swing due to a lateral rocking of the doll when recumbent, and retard its movement whereby it closes the eyes gradually, and to slip said rod in the reverse direction when the doll is uprighted, whereby its return movement in opening the eyes is free and relatively rapid. 20

In testimony whereof we have signed our names to this specification in the presence of two subscribing witnesses.

ROBERT A. THOMSON.
GORDON ALVIS.
